UNITED STATES PATENT OFFICE.

JAMES EDWARD DAY, OF ISABELLA, MANITOBA, CANADA.

GATE-HINGE.

1,358,710.

Specification of Letters Patent. Patented Nov. 16, 1920.

Application filed March 26, 1919. Serial No. 235,160.

To all whom it may concern:

Be it known that I, JAMES E. DAY, a subject of the King of England, residing at Isabella, in the Province of Manitoba and 5 Dominion of Canada, have invented new and useful Improvements in Gate-Hinges, of which the following is a specification.

The purpose of the invention is to provide a hinge for use in conjunction with 10 gates and similar closures whereby the use of a spring is avoided and yet such gate automatically returned to closed position after having been opened. To this end the invention comprises a novel hinge for supporting the gate, door or other closure device at the lower end, this hinge operating 15 to raise the center of gravity of the door or gate when the latter is opened, so as to insure its swinging to the closed position 20 immediately the gate or door is released, the hinge providing, when the door is in closed position for bringing the center of gravity to its lowest point at this time.

The invention is illustrated and described 25 in a specific embodiment, to which, however it is not to be restricted. The right is reserved to make such changes or alterations as the actual reduction to practice may suggest, in so far as such changes or alterations 30 are compatible in spirit with the annexed claims.

The same numerals of reference designate the same parts throughout the several figures of the drawing, wherein:

35 Figure 1 is a view in front elevation of a gate employing the improved hinge.

Fig. 2 is a perspective view of portion of the structure shown in Fig. 1 but illustrates the gate in open position.

40 Fig. 3 is a section on the line 3—3 of Fig. 1.

Fig. 4 is a section on the line 4—4 of Fig. 1.

Fig. 5 is a perspective view of one of the 45 elements comprised in the lower hinge.

Fig. 6 is a perspective view of another of the elements comprised in the bottom hinge.

50 Fig. 7 is a perspective view of the third or remaining element comprised in the bottom hinge.

As shown, the invention is employed in conjunction with a gate 1 which is of the usual character of swinging gate, being 55 made with an open frame and wire stretched across this frame. It is obvious, however,

that the gate *per se* is not to be restricted to this construction. The gate is swingingly attached to a post 2 and latches to a post 3, these two posts defining the gate opening 60 which the gate, when in closed position, is intended to close.

A keeper 4 is mounted on the post 3 and its construction is such, as is apparent in the drawing, as to permit the engagement 65 of the spring latch 5 which is carried by the gate 1 to whose frame it is attached. The gate is designed to swing to the open position to either side of the posts 2 and 3 and the construction of the keeper makes 70 for the engagement of the latch when the gate swings to closed position from either direction in which it is opened.

The gate is hingedly attached to the post 2 and this hinged connection provides an 75 upper hinge which is in the form of a bolt 6 inserted transversely through the post 2 and secured in place therein by a nut 7. This bolt is formed with an upstanding stud 8 which engages in an eye 9 appropriately carried by the frame of the gate. The weight of the gate obviously operates to keep the eye in engagement with the stud but at the same time permits angular movement of the eye relative to the stud and its 85 attendant blade.

The bottom hinge comprises a bolt 10 also inserted transversely through the post 2 and secured in place therein by a nut 11. This bolt 10, however, is formed with a disklike 90 head 12 the axis of which is at right angles to the axis of the bolt and this head lies with its flat faces in horizontal planes. The head is formed with a central eye 13 and with radially projecting teeth 14 on its upper 95 face, these teeth 14 extending from the eye 13 to the periphery of the head. Resting upon this head 12, a second element of the hinge is carried, this second element comprising a disklike body portion 15 formed 100 with a central eye 16 and with radially disposed teeth on its underface extending from the eye to its periphery. The teeth on the body portion 15 correspond with the teeth 14 on the head 12, so that when the body 105 portion 15 is placed upon the head the two may effect an interlocking engagement which prevents relative angular movement. This body portion 15 is secured to the head 12 by means of a bolt 17 passed through the 110 eyes 16 and 13 with its head resting on top of the body portion 15 and with the nut 18

which is secured to the bolt's threaded lower end abutting the underface of the head 12. The element of the hinge comprising the body portion 15 is formed at diametrically opposite sides with radially projecting arms 19 at the extremities of which there are upstanding studs 20.

The third element of the lower hinge is attached to the gate 1 and this third element comprises a clamp 21 which is secured to the gate frame. Formed with this clamp 21 there is a yoke 22 formed at its extremities with forks 23 which straddle the studs 20, the studs resting in the crotches of the forks.

In applying the invention, no great care need be exercised in mounting the upper hinge nor in mounting the post-engaging element of the lower hinge. In attaching that part of the hinge comprising the body portion 15 to the head 12 of the post-engagement element, however, the said body portion should be so set that its arms 19 are made to stand in a plane at right angles to the plane of the gate when the latter is in closed position. Thus the two forks of the yoke engage both studs 20 with the gate in closed position but in the event that the gate is opened, one or the other of the forks and the attendant stud 20 become the pivotal member of the lower hinge, the remaining fork leaving its attendant stud with the result that that edge of the gate adjacent the post 2 is thrown out of parallelism with the post, the lower end of the gate being farther spaced away from the post than the upper end, whereby the forward end of the gate is raised, so that when the gate is released it must perform swing back to closed position in which position the forward or free end is at the lowest level at which it can stand in any position of the gate on either side of the gate opening.

Obviously the particular form of lower hinge makes it unnecessary to exercise great care in its attachment to the gate post, that portion of the hinge carried by the post con-

sisting of two parts relatively adjustable making for the right positioning of that element of the hinge carrying the studs 20 so that the studs may be positioned to swing 50 the gate directly into closure position. With the post engaging element of the hinge in one part instead of two as shown and should it not be initially positioned properly, the gate would not swing to a stand in 55 the exact position of closure.

The invention having been described what is new and useful is:

1. A gate hinge comprising a yoke having 60 means for attachment to a gate, the said yoke being formed with forks at its ends, a member for attachment to the gate support, the said member being formed with a disklike head designed to lie with its upper face in substantially a horizontal plane, a second 65 member formed with a disklike body and with laterally extending arms on either side, the said arms being formed at their extremities with upstanding studs which the forks 70 of the yoke engage, and means connecting the said body to the said disklike head.

2. A gate hinge comprising a yoke having 75 means for attachment to a gate, the said yoke being formed with forks at its ends, a member for attachment to the gate support, said member being formed with a disklike head having its upper face disposed in a substantially horizontal plane and formed with a plurality of radially projecting teeth, 80 a second member formed with a disklike body and with corresponding teeth and resting upon the disklike head of the first member, the second member being formed with laterally extending arms having upright 85 studs at their extremities with which the forks of the yoke alternately engage, and a bolt passing through the disklike head and disklike body to detachably secure them together.

In testimony whereof I affix my signature. 90

JAMES EDWARD DAY.
